(57) **CLAIM**

The ornamental design for a female gas connector, as shown and described.

DESCRIPTION

FIG. 1 is a perspective view of a female connector.

FIG. 2 is a front view of the female gas connector.

FIG. 3 is a left view of the female gas connector.

FIG. 4 is a right view of the female gas connector.

FIG. 5 is a top view of the female gas connector.

FIG. 6 is a bottom view of the female gas connector.

FIG. 7 is a front view of the female gas connector, shown connected to a gas bottle and a male connector; and,

FIG. 8 is a side view of the female gas connector, shown connected to a gas bottle and a male connector.

The broken lines depict environmental subject matter only and form no part of the claimed design.
